United States Patent Office

Des. 194,725
Patented Feb. 26, 1963

194,725

DESK PAD OR SIMILAR ARTICLE

Angelo F. Monteverdi, Beverly Hills, Calif., assignor to
Monteverdi Young, Inc., Los Angeles, Calif., a corpora-
tion of California

Filed Apr. 30, 1962, Ser. No. 69,898

Term of patent 14 years

(Cl. D74—1)

FIG. 1 is a top plan view of the desk pad embodying my new design;

FIG. 2 is a rearward end view thereof;

FIG. 3 is a bottom plan view thereof;

FIG. 4 is an enlarged fragmentary sectional view thereof taken on the line 4—4 of FIG. 1; and

FIG. 5 is a top perspective view of a modified form of the desk pad shown in FIG. 1 having two desk pen receptors mounted at the top thereof.

I claim:

The ornamental design for a desk pad or similar article, substantially as shown and described.
